Lyleton E. Renney

BY *Benj. Webster*
ATTORNEY

UNITED STATES PATENT OFFICE.

LYLETON E. RENNEY, OF STOCKTON, CALIFORNIA.

AUTOMATIC RADILOG.

Application filed January 26, 1925. Serial No. 4,904.

To all whom it may concern:

Be it known that I, LYLETON E. RENNEY, a citizen of the United States, residing at Stockton, county of San Joaquin, State of California, have invented certain new and useful Improvements in Automatic Radiologs; and I do declare the following to be a full, clear, and exact description of the same, reference being had to the accompanying drawings, and to the characters of reference marked thereon, which form a part of this application.

This invention relates to improvements in the radio broadcasting art, and particularly to apparatus for receiving broadcasted signals.

The particular object of the invention is to provide a readily attachable and detachable and interchangeable chart element on which may be entered a log for readily and quickly and automatically finding the different positions of the condenser dials necessary for "bringing in" any certain station through the receiving apparatus.

By means of my improved log the finding positions on the dials for different stations may be charted and when once definitely charted for the receiving set in a given location, thereafter the log may be used in bringing in such stations without the necessity of close tuning each time it is desired to locate such station.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a perspective view of a fragmentary portion of a receiving apparatus showing my improved log installed thereon ready for use in service.

Fig. 2 is a front elevation of the chart element arranged for use in connection with the receiving set for logging the stations, as will be hereinafter described.

Fig. 3 is a perspective view of a straight-edge element used in connection with my log.

Fig. 4 is a fragmentary sectional view on a line 4-4 of Fig. 1.

Referring now more particularly to the characters of reference on the drawings, the letter A designates a typical radio receiving apparatus on which are the condenser or station finding dials 2, 3 and 4 respectively.

It is to be understood that my improved log may be used in connection with receiving apparatus of various kinds and of different constructions, the chart element being differently constructed to be accommodated thereto, as will be apparent from the following description.

My improved device comprises a semi-flexible element 5 which may be of cardboard or any similar material which will readily receive writing upon its surface. The lower edge of the element 5 is cut out or notched as at 6, 7, and 8 respectively to provide bearing and engaging portions to fit over the bearing pins 9 of the dials 2, etc.

The outer edge of the member 5 is preferably cut to be circumferential with each of the dials 2, 3, and 4 respectively so that the finished product is in effect three semi-circular elements 1^a, 1^b, and 1^c connected together by adjacent webs 10, each of the semi-circular elements being of a greater diameter than the diameter of the dial in connection with which it is to be used.

A small straight edge 11 made of thin celluloid or any other desired material is swiveled adjacent each of the notches 6, 7 and 8 and is movable over the face of its adjacent semi-circular element for a purpose as will presently appear.

When the device is to be used in connection with the receiving set the dials are set on their pins so as to leave a slight space 12 between the dial and the face of the panel of the receiving apparatus A. My improved chart element 5 is then inserted back of the dials and the notches 6, 7 and 8 fitted over the pins 9 of the dials. There being a close fit between the dials themselves and the chart 5 and the panel of the receiving set, this holds the chart from displacement

transversely from the panel. The notches 6, 7 and 8 fitting over the pins act as bearing elements and prevent the displacement of the chart longitudinally of the panel.

5. Thus the chart element is in constant fixed position with respect to the dials and even though different charts be interchanged the relative position of each of the dials will always be the same whenever the charts are

10. positioned back of the same. The faces of the different circular elements 1^a, 1^b and 1^c are ruled with circular lines 13 concentric with the dials, as a matter of convenience, although these may be dispensed with if

15. desired.

The use of the chart in logging the different stations to be brought in over the receiving apparatus from a certain position of the latter is accomplished in the following manner: The element 5, with nothing written on its face other than the curved lines, is inserted back of the dials and fitted in position over the pins. The several dials are then moved to tune or bring in a certain station in the most effective manner.

20. Each of the dials has on it a master indicating index line 14. When the station has been closely tuned the user then moves the straight edge 11 adjacent each dial over the face of its corresponding circular member to line up with the corresponding index line 14. A pencil or other writing element is then used to draw a line 15 from the index line on the dial across the face of the chart and the indicia 16 for the station which has been tuned in is then written adjacent that line. In this connection the lines 13 serve as guides for the user, so that he may write the indicia 16 in such a manner that the chart when finally logged will have a neat and symmetrical appearance.

25. As each new or different station is tuned in this operation is repeated until the chart is completely logged with all stations desired. If one chart is not sufficient for logging all the stations which can be brought in over the receiving apparatus other charts may be interchangeable therewith.

30. It will be apparent that after all stations are duly logged in the manner indicated that the charts can be used at will for bringing in any of the logged stations instantly without any close tuning of the apparatus, merely by moving the dials until the index lines line up with the station lines made on the chart in the manner indicated for the particular station which it is desired to bring in.

35. The utility of my improved logging chart will be entirely obvious to those skilled in the handling of radio receiving apparatus, and its simplicity, interchangeability, and positiveness will also be self-evident.

40. In addition to the obvious advantages to be gained by its use, the use thereof will

also permit a much finer tuning of the apparatus to be had, since after certain well known stations have been logged then the apparatus can be used so that the index lines on the dials may be worked between the log lines of already charted and logged stations and in this way different and theretofore uncharted stations may be gradually tuned in and logged.

The celluloid members 11 being thin, they do not occupy any appreciable transverse space, and may thus be permanently associated with the chart so as to be always handy when wanted.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A station logging means for radio receiving apparatus comprising a chart member arranged to fit immediately adjacent the tuning dials of the apparatus, said dials each having an index-mark thereon adjacent its edge whereby when tuning for different stations said mark will align with different portions of the chart around the dial-circle, and point marks may be made on said chart adjacent the dial mark, and means permanently mounted with the charts for enabling radiating lines to be drawn outwardly on the charts from the point marks made thereon.

2. A station logging means for radio receiving apparatus comprising a chart member arranged to fit immediately adjacent the tuning dials of the apparatus, said dials each having an index-mark thereon adjacent its edge whereby when tuning for different stations said mark will align with different portions of the chart around the dial-circle, and point marks may be made on said chart adjacent the dial mark, and a straight edge for each chart permanently pivoted thereon adjacent the plane of the axes of the dials, whereby on turning said straight edge to register with each point-mark made on the chart, a substantially radial line may be drawn on the chart outwardly from said mark.

3. A single logging chart element for use in connection with radio receiving apparatus having a plurality of tuning dials, such chart element being arranged to be removably mounted back of all the dials, and means for maintaining a constant relation

between the chart and the dials so that after logging indicia has been recorded on the chart in co-operation with each of the dials, thereafter such indicia will always assume 5 the same position relative to the dial corresponding thereto whenever the chart is inserted back of the dials.

4. A logging chart element for use in connection with radio receiving apparatus 10 having a plurality of tuning dials mounted

on pins, comprising a single flat member to fit back of all of the dials, the flat element having notches in one edge, one for each dial pin, and arranged to fit over the pins to cause the chart element to assume and hold the same position relative to the dials each time it is inserted behind the same. 15

In testimony whereof I affix my signature.

LYLETON E. RENNEY.
